UNITED STATES PATENT OFFICE.

EDWARD H. McCRAHON, OF SYRACUSE, NEW YORK.

PUTTEE.

1,367,065.

Specification of Letters Patent.

Patented Feb. 1, 1921.

Application filed September 14, 1917. Serial No. 191,370.

To all whom it may concern:

Be it known that I, EDWARD H. McCRAHON, a citizen of the United States of America, and resident of Syracuse, in the county 5 of Onondaga, in the State of New York, have invented new and useful Improvements in Puttees, of which the following, taken in connection with the accompanying drawings, is a full, clear, and exact description.

10 This invention relates to what are commonly known in army circles as puttees.

Heretofore puttees for the use of soldiers have been made by winding a strip of cloth about the leg and securing it in place by 15 means of a string or piece of tape wound transversely around the leg and suitably fastened.

20 My object is to produce an article of this character which is knitted all in one piece and adapted to be pulled on over the foot and to rest upon the leg, and at the same time have certain portions of the article provided with knitted ribs which are tensioned upon the leg for the purpose of holding 25 the puttee in position.

25 My invention, therefore, consists in the several new and novel features of construction and operation hereinafter described and specifically set forth in the claims hereunto 30 annexed.

It is constructed as follows, reference being had to the accompanying drawings, in which—

35 Figure 1 shows a view of the puttee with the cuff at the upper end extended, but showing the position of the cuff when folded back in dotted lines.

40 Fig. 2 is a vertical section through the upper portion only of the puttee illustrating the cuff in its turned down position.

45 Figs. 3 and 4 are enlarged views of a portion of the puttee or legging when in normal position and when longitudinally stretched, respectively.

50 Similar reference letters indicate corresponding parts.

—*a*— is the puttee as a whole and is constructed preferably by knitting it into the form shown, and at the same time knitting 55 into it the transverse ribs —*b*—, these ribs being so knit as to be less expandible than the main body portion of the puttee so as to form a tension over the leg and to serve to hold it in position, and likewise to prevent the garment from wrinkling transversely, as otherwise would be the case if they were

omitted. These ribs are preferably raised outwardly and form a sunken portion or channel —*k*— upon the opposite side of the puttee.

60 Adjacent the ribs —*b*— are additional ribs —*e*— extending inwardly from the puttee and forming a sunken portion or channel —*f*— upon the outside of the puttee, such sunken portion in normal tensioned position 65 being relatively narrow longitudinally of the puttee and tensioned to lie adjacent to and preferably partially beneath the ribs —*b*— and being relatively flexible in the direction of length of the puttee to permit considerable longitudinal elasticity.

70 The sunken portions —*k*— in normal tensioned condition tend to lie beneath the respective ribs —*e*—, such normal condition being indicated in Fig. 3, while in longitudinally extended position when the legging is stretched, the parts normally position themselves as shown in Fig. 4, illustrating the relatively great longitudinal extensibility of the legging, permitting its adaptability to a 80 greater range of persons of different sizes.

75 The lower portion —*i*— beneath the lowest rib —*b*— is preferably tightly knit to grip the ankle of the wearer, substantial elasticity at this point being practically unnecessary.

85 Near the upper end of the garment, I construct the contracted portion —*c*— which is knit in the opposite direction, but slightly smaller in circumference than the main portion of the garment so as to rest in the smaller portion of the leg just above the calf and below the knee, thereby serving to hold the garment as a whole at that place.

90 —*d*— is the cuff which is likewise knit as a part of the garment, although it may be secured by stitching and is adapted to be turned over, as shown in dotted lines in Fig. 1, and also as in cross section as shown in Fig. 2, the whole garment thereby completing a regulation puttee.

95 The section —*d*— may, as illustrated, be ordinary, so-called “purl knitting” where-in the needles knit first a course of loops in one direction and then a course of loops in the other direction. The section —*c*— may, as illustrated, be ordinary rib knitting in which alternate needles are drawn in opposite direction to cause alternate stitches to be drawn to opposite sides of the fabric. 105 The intermediate section —*b*— may, as illustrated, be knitted by “purl” knitting

with several courses in succession drawn to the same side of the fabric to form the oppositely projecting ribs —e— and —h—.

The entire garment is knit in a single strip, and then sewed together longitudinally of the puttee.

10 While I prefer to construct the puttee by knitting, yet I do not limit myself to a knit puttee, as it would be evident that it may be constructed of cloth and provided with transverse bands, as shown, which may be more or less of an elastic nature for the purpose of holding the same in position.

What I claim is:

15 1. A puttee consisting of a knitted body formed with circumferential ribs projecting from both the inner and outer side of the puttee, said ribs having a circumferential elasticity less than that of the main portion 20 of said body.

2. A puttee having a knitted body and knitted circumferential ribs having longitudinal elasticity less than the main portion 25 of the body, and having an upper portion knitted transversely of the body portion and of less circumference than the body portion, but more elastic than the body portion.

3. A puttee having a knitted body and knitted circumferential ribs having longitudinal elasticity less than the main portion 30 of the body, and having an upper portion knitted transversely of the body portion and of less circumference than the body portion, but more elastic than the body portion, and 35 having a cuff adapted to fold down and over said upper elastic portion.

4. A puttee formed of a single knitted piece of material and having a longitudinal seam uniting said piece of material into a 40 tubular structure, said knitted material comprising a series of ribs extending around the puttee and of less circumferential elasticity than the adjacent portions of said material.

45 5. A puttee formed of a single knitted piece of material and having a longitudinal seam uniting said piece of material into a tubular structure, said knitted material com-

prising a series of ribs extending around the puttee and of less circumferential elasticity than the portions of said material between said ribs, said material having an upper part of less circumference than the adjacent parts but of greater circumferential elasticity than said adjacent parts. 50

6. A puttee formed of a single knitted piece of material and having a longitudinal seam uniting said piece of material into a tubular structure, said knitted material comprising a series of ribs extending around 60 the puttee and of less circumferential elasticity than the portions of said material between said ribs, said material having an upper part of less circumference than the adjacent parts but of greater circumferential 65 elasticity than said adjacent parts, and a turned down cuff substantially covering said upper part of less circumference.

7. A puttee having a knitted body and knitted ribs extending around the puttee 70 and having circumferential elasticity less than the main portion of the body, and additional portions adjacent the ribs relatively elastic longitudinally of the puttee.

8. A puttee having a knitted body and 75 knitted ribs extending around the puttee and having radial elasticity less than the main portion of the body, and sunken portions adjacent the ribs and extending parallel with the ribs and of relatively great 80 elasticity in the direction of length of the puttee.

9. A puttee consisting of a knitted body and knitted circumferential ribs projecting 85 inwardly and outwardly from the puttee and normally lying partially underneath each other and permitting considerable extension of the puttee in the direction of its length while being less elastic circumferentially than the body portion of the puttee. 90

In witness whereof I have hereunto set my hand this 8th day of September, 1917.

EDWARD H. McCRAHON.
